UNITED STATES PATENT OFFICE.

CHRISTIAN F. T. MELZER, OF DETROIT, MICHIGAN, ASSIGNOR OF TWO-THIRDS TO EDWARD MARTIN, OF SAME PLACE.

CIGAR-MOLD.

SPECIFICATION forming part of Letters Patent No. 387,796, dated August 14, 1888.

Application filed February 13, 1888. Serial No. 263,926. (No model.)

To all whom it may concern:

Be it known that I, CHRISTIAN F. T. MELZER, a citizen of the United States, residing at Detroit, in the county of Wayne and State of Michigan, have invented certain new and useful Improvements in Cigar-Molds; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The invention consists in providing the cells of a matrix or cigar-mold with a series of cutting blades or points, which are located at the tip or head end of the bunch-forming cells of a cigar-mold.

The object of my invention is to provide a cigar-mold with means whereby, when the cigar-bunches are being pressed or molded, the tip or mouth end of each cigar-bunch will be provided with a slit, so that when the finishing-wrapper has been applied the cigar will draw easy, thereby making what is known as an "easy" drawing or smoking cigar.

In the common practice of making cigar-bunches in molds the tip or mouth end becomes too firmly pressed, thereby making a hard drawing or smoking cigar.

The object of my invention is to overcome this difficulty.

With reference to the accompanying drawings, I herein set forth my invention, the essential features being pointed out particularly in the claims.

In the accompanying drawings, Figure 1 represents the detached parts of a cigar-mold, like parts being broken away. Fig. 2 is an edge elevation of the parts of the matrix united or closed. Fig. 3 is a longitudinal central vertical section through one of the cells of the matrix, the parts being coupled, as in Fig. 2. Fig. 4 is a like section showing a slight modification. Figs. 5 and 6 represent the cigar-bunches as removed from the mold or matrix.

In the drawings, A represent the base or female portion of an ordinary cigar-matrix; B, the top or male portion. a is a dowel pin or lug attached to the end of the female part,

which, when the two parts of the matrix are coupled, enters the hole a' of the male part B for locking the parts together, all of which are old and in common use. The cigar-bunches are formed in the usual way by placing in the cells Z of the female part the tobacco, then placing the part B over the part A and forcing the parts together under a suitable press, thereby forcing the raised male former Z' into the cell Z of the female part, as shown in Fig. 2, thereby giving to the cigar-bunches the desired form. I attach in the longitudinal center of each male cell or former Z' at the top or mouth-forming end a projecting cutting-blade, f, (see Figs. 1, 2, and 3,) which blade, when the parts of the matrix are united, as in Figs. 2 and 3, will cut through the point or mouth end of the cigar-bunch, thereby forming the slit e, as shown in Fig. 5, which slit, when the wrapper has been applied to the cigar-bunch, forms an air-passage in the cigar, thereby forming an easy-drawing cigar. The projection of each blade f should be sufficient, so that when the parts of the matrix are coupled, as in Figs. 2 and 3, the blade will cut through the cigar-bunch at the tip end, the cutting-edge 2 meeting the face of the cell at 3. (See Fig. 3.) The angle of the cutting-edge 2 is made to coincide with the angle of the cell Z, as shown in Fig. 3, or a series of pins, f, as shown in Fig. 4, may be used in place of the cutting-blades, which pins form a series of perforations, e', as shown in Fig. 6. However, I prefer the blades f, as they make a better opening or separation of the tobacco of the cigar-bunch at the mouth or head end, as shown in Fig. 5.

The blades f are made fast to the tip ends of the male parts Z' of the matrix, so that when the part B of the matrix is lifted from the part A the blades f will move with the part B and draw out of the cigar-bunches, leaving the slot e in each cigar-bunch. The blades f being made fast to the part B, when the parts A and B are placed under suitable press the blades f will cut through the tobacco in each cell at the tip or mouth end.

Having thus fully set forth my invention, what I claim as new, and desire to secure by Letters Patent, is—

1. In an organized cigar-mold, the combi-

nation of the two body parts adapted to be locked together, each part having a portion of a cigar-bunch-forming cell located therein, the projecting cutting-blade located in the cigar-bunch-forming cell at the tip or head end, said blade being made fast to one of the body parts, the angle of its cutting-edge coinciding with the angle of the cell Z , substantially as and for the purposes specified.

10 2. In a cigar-matrix, the combination of the parts A B, each part having cells formed

therein, as set forth, the cutting-blades f , located in the tip or mouth end of the cells Z' , said blades being made fast to the part B, substantially as and for the purposes set forth.

15

In testimony whereof I affix my signature in presence of two witnesses.

CHRISTIAN F. T. MELZER.
